Primary Examiner—Charles A Rademaker*(74) Attorney, Agent, or Firm*—Banner & Witcoff, Ltd.(57) CLAIM

The ornamental design for a handset, as shown and described.

DESCRIPTION

FIG. 1 is a perspective front view of a handset showing our new design;

FIG. 2 is a front view thereof;

FIG. 3 is a rear view thereof;

FIG. 4 is a right side view thereof;

FIG. 5 is a left side thereof;

FIG. 6 is a top view thereof; and,

FIG. 7 is a bottom view thereof.

The broken line showing of the environmental structure of the handset and the unshaded regions within the broken lines in FIGS. 1–7 is for illustrative purposes only and forms no part of the claimed design.
